TO RESEARCH & DEVELOPMENT CORPORATION

HEAT-EXCHANGE DEVICE

Application filed May 20, 1930. Serial No. 454,013.

The invention relates to heat exchange devices and has as an object the provision of a device for heating or cooling liquids by contact with a wall the exterior of which is in contact with a gaseous medium.

It is a further object of the invention to provide a heat exchange device providing a tortuous passage for a liquid in contact with a wall exteriorly contacted by a gaseous medium of different temperature so arranged that substantially the entire surface of the wall is utilized for heat conduction and that portions of the liquid are caused to move more slowly than other portions thereof to provide a homogeneous temperature throughout the body of the liquid.

It is a further object of the invention to provide a heat exchange device comprising spaced corrugated plates so arranged as to present no direct path for liquid to flow therebetween but forcing the liquid to flow in a tortuous path and provided with means to space the plates apart and to correctly locate the plates relative to each other in assembly, said means providing internal bracing for the plates.

It is a further object of the invention specifically to provide an oil cooler for use with internal combustion motors.

Further objects of the invention will appear from the following description when read in connection with the accompanying drawings showing illustrative embodiments of the invention and wherein:

Fig. 1 is an end view of an oil cooler;

Fig. 2 is a side elevation of an oil cooler partly broken away;

Fig. 3 is a plan view of the heat exchange element of the cooler partly broken away;

Fig. 4 is a detail vertical cross section of a form of the device wherein the heat exchange elements are arranged in parallel suitable, for instance, for use as an automobile radiator;

Fig. 5 is a detail horizontal section on line 5—5 of Fig. 4;

Fig. 6 is a detail perspective view, the end shown in vertical section to illustrate the structure of the heat exchange device, the arrangement shown being that adapted for an

oil cooler such as shown in Figs. 1 to 3 inclusive; and

Figs. 7 and 8 are detail perspective views shown in end section of modified forms.

As shown in Figs. 4 and 6, the heat exchange elements constructed in accordance with the invention are formed of corrugated plates 10, 11 shown as formed with angular corrugations although it is obvious that curved corrugations may be utilized in the same manner.

To space the plates 10, 11 apart and to properly locate the corrugations of the two plates with respect to each other so as to provide a tortuous path for liquid flowing therebetween, there are shown a plurality of spaced strips 12 which are likewise corrugated but with corrugations considerably more shallow than are the corrugations of plates 10, 11.

The strips 12 are as shown applied to one of the plates as for instance plate 10 with the apices of the interiorly projecting corrugations of plate 10 in contact with the apices of the oppositely directed corrugations of the strip 12 and the plate 11 is then placed into contact with the strips 12 with the apices thereof in contact with the alternate corrugations of the strips. The result of such assembly is that the corrugations of the plates 10 and 11 are in nested relation but spaced apart from each other providing a zigzag path for flow of liquid between the plates, the spacing being such as to cause a slight overlap of the inwardly extending corrugation crests.

Since the strips 12 are provided with corrugations more shallow than the corrugations of the plates 10, 11, the liquid flowing between the plates has access to the inner surfaces of the plates 10, 11, not only between the strips 12 but behind the same and the liquid flowing between the plates will flow more rapidly in the spaces between the strips 12 than does the liquid which enters the spaces behind the strips. There will thus result a multitude of eddies in the liquid causing the liquid to be thoroughly mixed as it flows between the plates and the entire body of liquid will be cooled or heated uniformly as it leaves the space between the plates.

In the assembly of the device the strips 12 and the inner surfaces of the plates are first "tinned" with solder and then the plates and strips pressed together are heated to cause the contacting portions of the plates with the strips to adhere by virtue of the solder thus providing a structure which is inwardly reinforced sufficiently to prevent moderate pressures from causing bulging of the plates.

0 In the form of the invention shown in Fig. 7 the strips 12 are replaced by "sheets" of wire mesh material 30 which sheets are each corrugated as a whole to the same depth as the strips 12 and tinned. There is thus 5 provided a structure which is more easily assembled and which provides a greater number of points of adhesion than provided by the strips. The wire mesh 30 will still cause a thorough mixing of the liquid flowing 0 through the device and will also give substantially the entire radiating surface of the corrugated plates.

In the form of Fig. 8 the strips 12 are replaced by wires 31 which are also corrugated 5 but provide a less mixing of the fluid as it flows between the plates.

In the utilization of the exchange element thus described as an oil cooler for use with internal combustion engines in the form shown 10 in Figs. 1 to 3 inclusive and 6, the plates of a desired width, that is a desired extent longitudinally of the corrugations, are assembled in such manner as to provide for flow of oil through the elements in-series. As shown in 15 Fig. 6 the first two plates 10 and 11 to the left of the figure have their end margins extended, lapping as at 13 and soldered together and into the opening thus provided a coupling pipe may be introduced and soldered 0 as for instance that shown at 14, Fig. 3. At the lower end of the plates 10 and 11 just referred to the plate 10 of the first pair of plates is lapped together with the plate 10 of the second element as indicated at 15, the 15 lapped margins being soldered together and also the margins of the plates 11 of these two elements are lapped as indicated at 16, the arrangement being such as to provide a header to receive liquid from the first vertical travel 10 between plates 10 and 11, which header is in communication with the second pair of plates.

By the provision of laps 17 and 18 shown at the top of Fig. 6, the next pair of elements is likewise connected and the arrangement is 15 continued throughout the number of elements which it is desired to utilize as for instance three pairs as shown in Figs. 1 to 3 inclusive.

As an outlet for oil from the final pair of plates of the series, a pipe 32 is shown as 30 inserted into the header between the last pair of plates 10, 11 which pipe is provided with coupling 19. The pipe 32 is shown as slotted at 33, the slot being wider at the end remote from the coupling than adjacent there- 35 to. By this construction the flow of oil will

be substantially uniform across the width of the last element from bottom to top thereof.

The thus assembled elements then have the ends of the spaces between the plates 10, 11 closed as by dipping the end of the assembled 70 device into a bath of solder leaving the spaces between the plates 10 and the plates 11 respectively open for passage of the gaseous medium as air in the case of the oil cooler.

The ends of the lower headers are shown 75 as provided with cleanout screw plugs 33 which may be removed to enable settling to be removed.

In utilizing the thus described structure 80 as an oil cooler there is shown a casing 21 as of sheet metal shaped into rectangular form with the ends turned into parallel flanges 22, 23 which may be secured together as by bolts 24 when the assembly indicated in Fig. 3 has been placed therein.

Desirably angle members 25 are secured 85 into each corner of the casing 21 to space the heat exchange element from the walls of the casing 21 to permit air to flow therebetween.

To direct air into the space between the 90 plates 10 and 11 of the assembly of Fig. 3, there is shown a flaring extension of the walls of the casing 21 indicated at 26.

In use of this device for cooling an internal 95 combustion engine as for instance of an automobile, the device is supported in any suitable manner as at one side of the motor with the flaring member 26 directed toward the stream of air from the fan of the motor and the oil passages of the device are placed into 100 the circulation of the oil of the motor by means of couplings 14 and 19. Desirably the device is connected in series with the usual oil filter, therefore being in a bypass of the main lubricant circulation to the bearing surfaces of the motor. This arrangement is desirable since experiments have shown that so connected the cooling of the oil will be sufficient with relatively small overall dimensions of the device and because in the bypass 110 the pressure upon the oil will be less than would be met with in the main oil circulation. Obviously however the device may be placed in the said main circulation system, in which event a larger device must be utilized 115 to provide passage of the large quantity of oil therethrough without developing too great internal pressures.

It is obvious that the device may be placed 120 as a section of the radiator of the automobile, and when so applied may be formed with a less number of vertical elements of greater height, if desired.

For other uses of the invention the elements 125 comprising plates 10, 11 and strips 12 may be connected to upper and lower headers 27, 28, as indicated in Figs. 4 and 5 in which arrangement the passage of liquid to be cooled through the elements would be in parallel.

While the wire mesh of Fig. 7 is shown ar- 130

ranged with the wires perpendicular and parallel respectively with the corrugations of the plates, it is obvious that all of the wires may be arranged diagonally to the plate corrugations, and for some purposes the latter arrangement may be preferable.

The device may be used for many different purposes as for instance oil coolers as described, automobile radiators, heat radiators for use in mechanical refrigeration, in the heating of liquids, and in fact in any use where liquid is to be cooled or heated by conducting heat to or from a gaseous medium of different temperature.

Minor changes may be made in the physical embodiment of the invention within the scope of the appended claims without departing from the spirit of the invention.

I claim:

1. A heat exchange element comprising, in combination, spaced deformed plates associated to provide a tortuous path for fluid flowing therebetween, a plurality of spaced elements between said plates spanning said deformities and contacting the plates at a plurality of spaced points whereby said fluid may surround said elements to provide heat exchange within the mass of the fluid, said elements providing heat conductivity between said mass and said plates.

2. An oil cooling device comprising, in combination, a plurality of heat exchange elements as claimed in claim 1 connected for flow of oil therethrough in series, means to connect the first and last of said elements to the lubrication system of a machine.

3. An oil cooling device comprising, in combination, a plurality of heat exchange elements as claimed in claim 1 arranged in parallel relation, headers connecting an end of each element with the adjacent end of the succeeding element to provide for flow of oil therethrough in series and means to connect the free ends of the first and last elements with the lubrication system of a machine.

4. An oil cooling device comprising, in combination, a plurality of heat exchange elements as claimed in claim 1 arranged in parallel relation, headers connecting an end of each element with the adjacent end of the succeeding element to provide for flow of oil therethrough in series, means to connect the free ends of the first and last elements with the lubrication system of a machine, and removable plugs in the ends of some of said headers for cleaning purposes.

5. A heat exchange element comprising, in combination, spaced deformed plates associated to provide a tortuous path for fluid flowing therebetween, spacing a plurality of spaced elements between said plates spanning said deformities and secured to the plates at a plurality of spaced points whereby said fluid may surround said means to provide heat exchange within the mass of the

fluid, said elements providing heat conductivity between said mass and said plates.

6. A heat exchange element comprising, in combination, spaced deformed plates inwardly presenting alternate convexities and concavities, those on each plate arranged in staggered relation to those on the opposed plate, spacing and turbulence producing means between said plates, said means comprising a sheet of foraminous material, said sheet contacting and secured to the inwardly directed crests of said deformities.

7. A heat exchange element comprising, in combination, spaced corrugated plates, the crests of the inwardly directed corrugations of each plate in staggered relation to the crests of like corrugations of the opposed plate, a plurality of turbulence producing and heat conducting spacing elements extending between said plates in the main direction of fluid flow therebetween, said elements comprising flat strips of heat conducting material spaced apart a distance substantially equal to their width, said strips contacting with and secured to the inwardly directed crests of the corrugations of the plates.

8. A heat exchange element, comprising in combination, spaced corrugated plates providing a tortuous passage therebetween, a plurality of spaced spacing elements between said plates, said elements corrugated to a less depth than said plates and with the distances between crests equal to the corrugations of said plates, the concavities of the corrugations of the elements contacting with the inwardly directed crests of the corrugations of the plates.

9. A heat exchange element, comprising in combination, corrugated plates so spaced apart that the crests of the inwardly directed corrugations stand closely adjacent a common plane, a plurality of spaced spacing and locating elements between said plates, said elements corrugated to register with the corrugations of said plates but to a less depth than the latter, the concavities of the corrugations of the elements contacting with the inwardly directed crests of the corrugations of the plates and secured thereto at a plurality of points along each of said crests.

10. A heat exchange element, comprising in combination, corrugated plates so spaced that the crests of the inwardly directed corrugations stand closely adjacent a common plane and opposite the concavities of the opposite plate corrugations, spacing and locating means comprising a plurality of wires extending at an angle to the said corrugations, said wires corrugated to register with the corrugations of the plates but to a less depth than the corrugations of the plates, the concavities of the wire corrugations contacting with and secured to the inwardly facing crests of the corrugations of the plates.

11. A heat exchange element, comprising

- in combination, a plurality of corrugated plates so spaced and arranged that the walls of the corrugations of each are parallel to those of the other with the inwardly directed crests closely adjacent a common plane, spacing and locating means between said plates comprising a sheet of wire mesh material corrugated as a whole to register with but corrugated to a less depth than said plates, some of the wires of said mesh extending at an angle to the corrugations of said plates, the inwardly directed crests of the plates contacting with the concavities of and secured to the corrugations of the mesh.
5. 12. An oil cooling device comprising, in combination, a plurality of parallel spaced elements each comprising a pair of spaced corrugated plates providing a tortuous path for liquid therebetween, the spaces between said plates at the edges thereof closed, an end of the outside elements closed and provided with means for coupling to an oil circulation pipe of a machine, the plates of the alternate ends of the elements overlapped with and connected to the plates of the adjacent elements to provide headers to enclose a path for oil flow through the assembled elements in series, an open ended casing enclosing the assembly and a flaring flange to direct a blast of air through the assembly lengthwise of the corrugations.
13. An oil cooling device comprising, in combination, a plurality of spaced elements each comprising a pair of spaced deformed plates providing a tortuous path for liquid therebetween, the spaces between the plates of each element at the edges thereof closed, an end of each outside element closed and provided with means for coupling to an oil circulation pipe of a machine, means to place each of the alternate remaining ends of said elements into communication with an end of an adjacent element to enclose a path for oil flow through said elements in series and means in the outlet end element to provide more restricted flow from said element adjacent the coupling than at the edge remote therefrom.
